UNITED STATES PATENT OFFICE

167,035

FOOD TRAY WITH EXTENDIBLE WINGS

Robert B. Karoff, New York, N. Y., assignor to
Novelty Utilities, Inc., New York, N. Y., a corporation of New York

Application March 1, 1952, Serial No. 18,745

Term of patent 14 years

(Cl. D44—10)

To all whom it may concern:

Be it known that I, Robert B. Karoff, a citizen of the United States and a resident of New York city, county and State of New York, have invented a new, original, and ornamental Design for a Food Tray With Extendible Wings, of which the following is a specification, reference being had to the accompanying drawing, forming a part thereof, in which:

Fig. 1 is a top perspective view of the food tray with extendible wings, showing my new design in contracted or closed condition;

Fig. 2 is a side elevational view thereof showing the same in closed condition;

Fig. 3 is an end elevational view thereof showing the same in closed condition; and

Fig. 4 is a top plan view thereof showing the wings thereof moved to an open serving position.

I claim:

The ornamental design for a food tray with extendible wings, as shown.

ROBERT B. KAROFF.
